WORD GAME APPARATUS COMPRISING GAME BOARDS, GAME PIECES AND A RACK THEREFOR

Frederick J. Lissandrello, Box 134B, R.D. 1,

Catskill, N.Y.

Filed May 17, 1963, Ser. No. 281,184

2 Claims. (Cl. 273—148)

This invention relates to the general field of educational and amusement devices and more specifically, the instant invention pertains to a competitive game involving word construction.

One of the primary objects of this invention is to provide game apparatus for use by a plurality of competitors in the formulation or spelling of words through the use of letter game pieces provided by chance to each competitor or player.

Another object of this invention is to provide a unique letter game piece rack to afford means for the collective stacking of the game pieces.

A further object of this invention is to provide a plurality of game boards, each game board being divided into a plurality of compartments of such size as to receive therein a single game piece.

Still another object of this invention is to provide game boards of the type described generally above, together with means to support the same at an inclined angle relative to a horizontal supporting means.

It is a still further object of this invention to provide a game piece rack together with means permitting the stacking of the game boards therein when the latter are not in active use.

Still further, this invention has as an object thereof, the provision of compartmental game boards and a plurality of playing pieces having alphabetical indicia disposed thereon, the pieces being adapted for positioning on the board in such order as to spell out various words.

This invention has, as still another object thereof, the provision of game apparatus of the type described which will provide education and amusement for both children and adults.

This invention contemplates, as a still further object thereof, the provision of game apparatus of the type described, the apparatus being non-complex in construction and assembly, inexpensive to manufacture and maintain, and which is durable in use.

Other and further objects of this invention will become more manifest from a consideration of the following specification when read in conjunction with the annexed drawings, in which:

FIGURE 1 is a perspective view of a game piece rack and a game board stacking device, including, in perspective, a plurality of game boards and game pieces positioned for active play, all in accordance with this invention;

FIGURE 2 is a top plan view of the game piece rack and of the game piece boards as stacked therein;

FIGURE 3 is a transverse detail, cross-sectional view, FIGURE 3 being taken substantially on the horizontal plane of line 3—3 of FIGURE 2, looking in the direction of the arrows;

FIGURE 4 is a detail cross-sectional view, FIGURE 4 being taken substantially on the vertical plane of line 4—4 of FIGURE 1, looking in the direction of the arrows;

FIGURE 5 is a front perspective view of a game board together with certain game pieces disposed thereon; and

FIGURE 6 is a perspective view of one of the game pieces.

Reference numeral 10 designates, in general, game apparatus constructed in accordance with the teachings of

2

this invention. The game piece and game board rack 10 is seen to comprise a substantially rectangular base plate 12 having a centrally-located substantially rectangular opening 14 formed therein. The base plate 12 may be formed of plastic material or any other suitable material, as desired.

Projecting laterally and upwardly from the base plate 12 are a plurality of upright side walls 16, 18, 20 and 22 having a substantially rectangular configuration. As is seen in FIGURES 1, 2 and 3, the side walls 16, 18, 20 and 22 are substantially perpendicular to the base plate 12 and the adjacent ends of the side walls are preferably integrally connected therewith. Each adjacent pair of ends of the side walls are also integrally connected and are disposed at right angles with respect to one another. As is shown, side walls 16, 18, 20 and 22 form a continuous panel designated, in general, by reference numeral 24.

Projecting laterally from each side wall 16, 18, 20 and 22, respectively, are a plurality of T-shaped dividers 26 that are integral therewith and with the base plate 12 from which they laterally and upwardly project, and which are also integral therewith. Each of the dividers 26 includes a substantially rectangular stem 28 to the outer edge of which is integrally connected a crosshead 30. The crossheads 30 are also of rectangular configuration.

The stems 28 on each side wall 16, 18, 20 and 22 are parallel to one another, and the crossheads 30 thereof are perpendicular to the stems 28 and are aligned with one another in longitudinally-spaced relation.

Each of the side walls 16, 18, 20 and 22, at their longitudinally-spaced opposed ends, is integrally connected with a substantially L-shaped retainer plate 31 that is also integral with the base plate 12 at the lower end thereof from which it upwardly projects. Each retainer plate 31 includes an upright substantially rectangular leg portion 32 which is parallel to the immediately adjacent stem 28, and a foot portion 34 extends toward and is aligned with the immediately adjacent crosshead 30.

Each adjacent pair of dividers 26 and each adjacent divider 26 and retainer plate 31 form therebetween compartments 36 having open front faces and upper ends, and each compartment 36 serves as a rack for one or more playing or game pieces 38.

Each of the playing or game pieces 38 is substantially rectangular in configuration and has imprinted, embossed, or otherwise affixed to one or opposite sides thereof, alphabetical characters, as is indicated by reference numeral 40. Preferably, but not necessarily, the same alphabetical character is carried on the opposed sides of each playing piece 38.

It will be noted that twenty-eight compartments 36 have been provided on the game board, and in each of the compartments 36, respectively, is stacked sixteen playing or game pieces 38 with the game pieces 38 in each rack having imprinted thereon one of the twenty-six letters of the alphabet. This utilizes twenty-six of the compartments 36. One of the remaining of the compartments 36 has stacked or racked therein another set of sixteen playing or game pieces 38 having only the letter "A" thereon, and the last of the compartments 36 has stacked or racked therein sixteen of the playing or games pieces 38 having the letter "E" thereon. Thus, there is provided a total of four-hundred-forty-eight playing or game pieces 38 of which thirty-two carry the letter "A" and the same number bear the letter "E."

The apparatus 10 includes a plurality of substantially hollow rectangular game boards 42 formed of a plastic or of other desirable materials, each of the game boards 42 comprising a substantially rectangular base wall 44 which has one side (back side) provided with an inwardly-extending, substantially hollow rectangular pocket 46 defined by a first pair of oppositely-disposed spaced

and substantially rectangular side walls 48, 50 spaced from one another in parallel relation, and a second pair of spaced and substantially rectangular, parallel side walls 52, 54.

Reference numeral 56 denotes, in general, a substantially U-shaped standard, one being provided, respectively, for each of the game boards 42. The standards 56 each includes a normally horizontal bight portion 58 (see FIGURES 1 and 4) from the opposed ends of which arise a pair of upstanding spaced and substantially parallel legs 60, 62 which terminate at their respective upper ends in diverging aligned arms 64, 66. The arms 64, 66 are received for pivotal movement within substantially hollow and oppositely-disposed pockets 68, 70 (see FIGURE 2) formed in the side walls 48, 50 adjacent the upper side wall 52. The bights 58 normally rest upon a playing support surface 72 such as, for example, a card table (not shown) when the standards 56 have been withdrawn from their respective pockets 46 and the boards 42 are disposed in playing position in the manner illustrated in FIGURE 1.

Each of the playing boards 42 has provided on the reverse or front side thereof a continuous integrally-formed peripheral flange 74, and the front side of the base wall 44 is also provided with a plurality of laterally-projecting, intersecting, horizontal and vertical divider strips 76, 78 having a substantially rectangular configuration and which are integrally connected with one another at right angles with respect to each other to provide a plurality of substantially rectangular compartments 80 designated, in general, by reference numeral 80, having such dimensions as to loosely receive one of the rectangular playing or game pieces 38 therein with the alphabetical characters thereof facing outwardly.

As is shown in FIGURES 1 and 5, the game board 42, through its dividers 76, 78 is partitioned into a plurality of horizontal and vertical rows of six of the compartments 80 giving rise, in "checkerboard" fashion to a total of thirty-six playing compartments 80. For purposes to be described, the outer edge of the flange 74 which extends downwardly from the upper left-hand corner of the game board 42 as viewed in FIGURES 1 and 5 is colored for a length of five of the compartments 80, the colored edge being designated at 74A. The horizontal divider strip 76A has its outer edge also colored and extends horizontally across five of the compartments 80. The vertical divider strip 78A also spans five of the compartments 80, and the horizontal portion of the flange 74 at the upper end of the left-hand portion thereof is also colored as denoted at 74B and extends horizontally across five of the compartments 80. Thus, it is seen that the colored portions of the flange 74 and of the divider strips 76, 78 encompass and outline a playing board having a total of twenty-five of the compartments 80.

When the game boards 42 are not in use, the standards 56 thereof are pivoted into their respective pockets 46 and the game boards are then inserted within the cavity 82 (see FIGURE 1) defined by the continuous panel 24 and the base plate 12 with the front faces of the playing boards 42 preferably facing downwardly.

The game apparatus 10, when set up in playing positions, as shown in FIGURE 1, contemplates competition between three competitors, but the game may be played with from two to five players. The object of the game is to spell out as many words horizontally and vertically as possible through the judicious placement of three or more successive ones of the playing or game pieces reading from left to right, or top to bottom, as viewed in FIGURES 1 and 5. One of the game boards shown in FIGURE 1 illustrates the arrangement of playing or game pieces 38 in the horizontal and vertical rows of compartments 80 embraced within the square bounded by the colored edges 74A, 74B, 76A and 78A, or, optionally, there is also shown in FIGURE 1 a game board 42 having playing or game pieces 38 arranged in hori-

5 zontal and vertical compartments bounded by the flange 64 and which, in the arrangement shown, spell two six-letter words. Under either system of play, to score, a player attempts to arrange his playing or game pieces 38 in such manner that three consecutive letters in each horizontal or vertical row of compartments 80 form a word, and subsequent game or playing pieces 38 may be added thereto in successive plays to form words having four, five, or six letters therein, all depending upon the selected game.

10 Thus, in a five-letter game, as illustrated at the left-hand side of FIGURE 1, the first three horizontal lines reading from top to bottom spell the words "THIRD," "RADIO," and "AVIEW," and the final horizontal line reads "KNOLL." The term "CENE" does not form a known word and hence, cannot be scored, per se, but since it includes the consecutive letters "NEE," it may be scored as a three-letter word.

15 Reading downwardly and from left to right, it is seen that this game board is arranged to spell out the words "TRACK," "HAVEN," and "DOWEL." The expressions "IDINO" and "RIEEL" do not form known words consisting of five letters and hence, cannot be scored. However, since the second, third and fourth letters of the expression "IDINO" form the three-letter word "DIN," this word may be scored. As will be seen, the final three letters of the expression "RIEEL" form the known three-letter word "EEL," and as such, may also be scored.

20 Also shown in FIGURE 1 is a game board 42 set up for six-letter competition. As illustrated therein, the upper horizontal row of compartments are provided with playing or game pieces 38 so arranged and disposed as to spell the word "STROLL," and the pieces 38 disposed in the vertical compartments 80 at the left-hand side of the game board 42 spell the six-letter word "SPRING."

25 To play the instant game, and assuming that the game racks and boards have been set up on a suitable support surface 72 in the manner illustrated in FIGURE 1 with all of the playing or game pieces disposed in their respective compartments 36, preferably, a plurality of the game pieces 38 being arranged in each of the game racks or compartments 36 and having but a single alphabetical character, a first player will remove a plurality of game or playing pieces 38. Assuming that four competitors are engaged in playing the game, each player, in succession, will select four, identical alphabetical characters or playing pieces 38 from their respective racks 36 and will keep one, while passing the others, singly, to his opponents. Each player then, in turn, will place the dealt playing or game pieces 38 arbitrarily in a selected one of the compartments 80. After the piece has been disposed within one of the compartments 80, the position thereof cannot be changed in subsequent plays. The playing or game pieces 38 are continued to be dealt by each player in turn until, if the five-letter game is being played, each player has received and placed in the compartments 80 of the game board 42 as bounded by the colored boundary strips, twenty-five of the game or playing pieces 38. If the game is to be that of the six-letter type, then of course, each player will be dealt thirty-six separate pieces.

30 When all of the compartments 80 for the five or six-letter games have been filled with the game pieces 38 by each player, the points accrued by each player are scored as follows:

35 In the five-letter word game each word of five letters is scored 10 points. Each four-letter word scores 5 points, and each three-letter word is valued at 3 points. Thus, and referring to the game board as shown in FIGURE 1 set up for the five-letter word game, the word "THIRD" gives the player 10 points, as do the word "RADIO," and "KNOLL," the word "AVIEW" scores 5 points, and the word "CENE" is rated at 3 points. These are the words which appear when the game board

is read horizontally. The same player will score in the following manner when the board is read vertically: For the word "TRACK" he will score 10 points, as he will for the words "HAVEN" and "DOWEL." For the word "DIN" in the expression "IDINO," and "EEL" in the expression "RIEEL," he scores 3 points each. Thus, the player has scored a total of 74 points.

A little different scoring is employed when playing the six-letter game. Since it is a little more difficult to conceive of six-letter words, and taking into consideration the fact that the playing or game pieces 38 are arbitrarily placed on the game boards 42 as the same are dealt to the individual players, each six-letter word is given a score value of 20 points. Thus, referring to FIGURE 1, the board set up for the six-letter word contest spells, horizontally, the word "STROLL" and vertically, the word "SPRING." The fortuitous placement of these letters as dealt to the player has enabled this player, in eleven plays, to score a total of 40 points, each six-letter word having a value of 20 points.

All words will be given proper evaluation except foreign words, proper nouns, prefixes and plurals. Present and past tense verbs may be used, and words may be repeated.

When a round of play is completed, that is, when either the five-letter word game or the six-letter word game has been completed, the game or playing pieces are emptied from the playing boards 42 and each letter is returned to its respective compartment in the rack.

A complete game is composed of rounds. A "round" has been defined above, and there must be, in each game, at least one or more rounds corresponding to the number of players. Thus, if there are two opponents, the game will include two rounds, or more, with three players, three rounds or more, with four players, four rounds or more, and with five players, five rounds or more.

This system enables each player to be the first in dealing out the letters and to be the first in play. To play first has a definite advantage because in all cases the first player will get one more play than the others, except when there are five players.

When all of the rounds have been played, all scores are totaled, and the winner is decided. Thus, one player who may lag behind in the earlier rounds, may be the eventual winner if he finishes strong.

Having described and illustrated one embodiment of this invention in detail, it will be understood that the same is offered merely by way of example, and that this invention is to be limited only by the scope of the appended claims.

What is claimed is:

1. A game apparatus comprising, in combination, a game piece and game board rack, said game board rack including a normally horizontal substantially rectangular

base plate having a central opening formed therein and a continuous panel projecting laterally from a side thereof and cooperating with said base plate to form a cavity, a plurality of substantially rectangular game boards 5 stacked within said cavity, said game boards being supported on said base plate, said game boards each having dimensions substantially equal to the length and width of said cavity, a plurality of spaced divider means projecting laterally from said panel and away from said cavity and upwardly from said base plate, said divider means cooperating with said panel and said base plate to form a plurality of substantially rectangular game piece-receiving compartments opening in a direction away from said panel, and a plurality of uniformly-shaped substantially rectangular game pieces stacked within each of said game piece compartments in face-to-face engagement and with the peripheral edges on three sides thereof of constantly abutting said panel and said divider means.

2. A game apparatus comprising, in combination, a game piece and game board rack, said game board rack including a normally horizontal substantially rectangular base plate having a central opening formed therein and a continuous panel projecting from a side thereof to form a substantially rectangular cavity, a plurality of sub-

stantially rectangular game boards stacked within said cavity, said game boards each having dimensions substantially equal to the length and width of said cavity, a plurality of spaced divider means projecting laterally from said panel in a direction away from said cavity and upwardly from said base plate, said dividers, said panel and said base plate forming a plurality of substantially rectangular game piece-receiving compartments having open upper ends and opening toward the outer periphery of said base plate, each of said divider means comprising a substantially rectangular panel extending from said base plate to substantially the upper peripheral edge of said panel and from said panel to the outer peripheral edge of said base plate, a substantially rectangular cross-head fixedly secured to the outer edge of each of said divider panels and said base plate, each of said cross-heads extending partially across each of the open sides of a pair of adjacent compartments and a plurality of playing pieces each having a substantially rectangular configuration and stacked in said compartments in face-to-face relation, said playing pieces having substantially the same length and width as corresponding dimensions of said compartments.
